[57] **CLAIM**

The ornamental design for a combined sprinkler support and hose coupler design, as shown and described.

DESCRIPTION

FIG. 1 is a perspective view taken from the top, front and left side of a combined sprinkler support and hose coupler showing my new design;

FIG. 2 is a top plan view thereof;

FIG. 3 is a bottom plan view thereof;

FIG. 4 is a left side elevational view thereof, the right side being a mirror image of the side shown;

FIG. 5 is a rear elevational view thereof; and

FIG. 6 is a front elevational view thereof.

It is to be understood that the sprinkler support is shown broken away in FIGS. 1 and 4 through 6 to indicate indeterminate length.
